UNITED STATES PATENT OFFICE

45 FRIEDRICH DUWE, OF MAINZ-KASTEL, GERMANY, ASSIGNOR TO MASCHINENFABRIK AUGSBURG-NUREMBERG A. G., OF NUREMBERG, GERMANY, A CORPORATION OF GERMANY

ACTUATING DEVICE FOR LEVER-DRAWBRIDGES

Application filed June 18, 1930, Serial No. 461,871, and in Germany June 18, 1929.

This invention relates to actuating means for so-called lever-drawbridges, and has generally in view to provide an actuating means of improved type for such drawbridges.

It is known in the art to actuate lever-drawbridges by means of elongated rigid racks. Such actuating means are, however, disadvantageous due to the necessity of providing special supports for the racks and because of the relatively great amount of space required to accommodate the racks and their supports.

Because of the foregoing and other reasons it has heretofore been proposed to employ 15 actuating means in the form of endless chains or cables which require comparatively less space than rigid racks for their installation. However, the use of chains or cables is not always possible, and, moreover, chains and 20 cables not only are unsafe but have a tendency to increase in length, with various consequent disadvantages.

Accordingly, the general object of the present invention is to provide an actuating means for lever-drawbridges which retains the desirable features and eliminates the undesirable features of rigid racks and chains or cables as actuating means for such drawbridges.

30 In the accompanying drawing the figure is a view in side elevation of a lever-drawbridge equipped with an actuating means constructed in accordance with one practicable embodiment of the invention.

35 Referring to the drawing in detail, *b* designates a portion of a lever-drawbridge carrying a sector *a* which is rollable on a horizontal support *e* to raise and lower the drawbridge.

40 A flexible rack composed of numerous short length sections d' , d'' , etc., which are pivotally connected together in end to end relation, is connected by a link or one of the end sections d of the rack to the sector a at the center thereof, and said rack is disposed

45

between spaced guide members f and g which are located above and extend parallel to the horizontal surface of the support e on which the sector a is rollable, and at a distance from said surface corresponding to the radius of the sector a , whereby longitudinal movement of the rack between said guide members is effective to roll said sector.

A windlass conventionally illustrated at *i* is mounted on a frame *k* and is inclusive of a pinion *h* cooperating with the rack to produce longitudinal movements thereof. This windlass preferably is located at or near the outer ends of the rack guide members, and at the side of the pinion *h* remote from the sector *a* the lower guide member *f* is extended downwardly as indicated at *f'* and the upper guide member is terminated short of said downwardly extended portion of the lower guide member, whereby, when the rack is moved to the right as viewed in the drawing to effect raising of the drawbridge, the rack sections *d', d'',* etc., after passing the outer end of the guide member *f* are free to pivot relative to each other and to gravitate downwardly along the extension *f'* as illustrated in the drawing by dotted lines. Thus it is apparent that the effective portion of the rack need be no longer than the length of the surface *e* and that the entire actuating means is disposed within a space corresponding in length substantially to the length of the guide members even when the drawbridge is raised. Consequently, space heretofore required to accommodate racks in the form of rigid bars when the drawbridge is raised may, by reason of the present invention, be utilized for other purposes. Moreover, the present actuating means obviously possesses the advantages of chain or cable actuating means as regards the desirable conservation of space, and of a rigid rack as regards the desirable features of this type of actuating means as compared with a chain or cable, and at the same time avoids the disadvantages inherent to both a rigid

rack or a chain or cable actuating means, because the present rack not only is flexible when not confined between the guide members *f* and *g*, but when confined between said 5 guide members is equivalent to a rigid rack.

From the foregoing description considered in connection with the accompanying drawing it is believed that the construction, operation and advantages of the invention will be 10 clearly understood. It is pointed out, however, that the structure shown may be modified and that the arrangement of elements may be varied in different respects within the spirit and the scope of the invention as 15 defined in the appended claims.

I claim:

1. In combination with a drawbridge inclusive of a sector, a support having a surface on which the sector is rollable to raise 20 and lower the drawbridge, a rack connected with the sector, said rack being composed of a plurality of rack sections pivotally connected together in end to end relation, elongated guide members between which said 25 rack sections are movable, said guide members being effective to prevent the rack sections disposed therebetween from pivoting relative to each other whereby the rack is operable in tension to raise the drawbridge and 30 in compression to close the same, a pinion engaged with the rack for moving the same longitudinally between said guide members, and means for actuating said pinion. 35

2. In combination with a drawbridge inclusive of a sector, a support having a surface on which said sector is rollable to raise and lower the drawbridge, a rack pivotally connected at one end with the sector at the center thereof, said rack being composed of a 40 plurality of rack sections pivotally connected together in end to end relation, elongated guide members substantially coextensive in length with the surface of the support over which the sector is rollable and between 45 which said rack sections are confined and held against pivotal movement relative to each other whereby the rack is operable in tension to raise the drawbridge and in compression to close the same, a pinion engaged with the 50 rack for moving the same longitudinally between said guide members thus to effect rolling of said sector to raise or lower the drawbridge, and means for actuating said pinion. 55

3. In combination with a drawbridge inclusive of a sector, a support having a surface on which said sector is rollable to raise and lower the drawbridge, a rack pivotally connected at one end with the sector at the center thereof, said rack being composed of a 60 plurality of rack sections pivotally connected together in end to end relation, elongated guide members substantially coextensive in length with the surface of the support over which the sector is rollable and between which 65 said rack sections are confined and held

against pivotal movement relative to each other whereby the rack is operable in tension to raise the drawbridge and in compression to close the same, said rack members extending parallel to said surface of said support above the latter, a pinion engaged with the rack for moving the same longitudinally between said guide members thus to effect rolling of said sector to raise or lower the drawbridge, and means for actuating said 75 pinion. 70

In testimony whereof I affix my signature.
FRIEDRICH DUWE.
